UNITED STATES PATENT OFFICE.

WILHELM MAX ROCKSTROH, OF DRESDEN-HEIDENAU, GERMANY.

PLATEN PRINTING-PRESS.

SPECIFICATION forming part of Letters Patent No. 729,223, dated May 26, 1903.

Application filed March 23, 1901. Serial No. 52,548. (No model.)

To all whom it may concern:

Be it known that I, WILHELM MAX ROCKSTROH, works manager, a subject of the Emperor of Germany, residing at Grenz street, 5 Dresden-Heidenau, in the German Empire, have invented certain new and useful Improvements in Platen Printing-Presses, of which the following is a complete specification.

10 In a platen printing-press the inking-roller frame is moved, as is well known, by means of a lever which is moved up and down by means of a cam and suitable connecting parts. In the case of large presses, however, the use 15 of a cam is disadvantageous and interferes with the proper working of the various parts.

This invention has for its object to obviate the use of a cam by substituting toothed gearing therefor. It is obviously desirable to 20 depart as little as possible from the usual type. In the present case this has been kept in mind, as will be seen from the accompanying drawings, in which—

Figure 1 is a side elevation of one example 25 of apparatus according to this invention. Fig. 2 is a sectional front elevation. Fig. 3 is a side elevation of a modification, and Fig. 4 is a sectional front elevation of the modification.

30 For the purpose hereinbefore mentioned it has been found most convenient in practice to cause the roller-frame lever to be operated through the usual connecting parts by a crank which is either permanently connected with 35 a toothed wheel driven intermittently by a main toothed wheel or is connected by a clutch with a toothed wheel driven continuously by a main toothed wheel.

In the example shown in Figs. 1 and 2 there 40 is a main toothed wheel *a*, which is driven in any suitable manner and engages with a smaller toothed wheel *b*, that is rigidly connected to the crank *e* by means of a short shaft *d*, mounted in bearings *c*. To the crank 45 *e* there is connected one end of an arm *f*, the opposite end of which is provided with a hook *f'*, which bears on a pin *g* of an arm *h*, rigidly connected to the shaft *i* of the roller-frame lever *k*. As the lever *k* has to make 50 only one upward-and-downward movement after each impression, the toothed wheel *a*, which is made much wider than the toothed

wheel *b*, has a portion of its periphery removed for a part of its width, Fig. 2, so that the toothed wheel *b* will be rotated only when it is in engagement with the unremoved portion of the periphery of the wheel *a*, which will cause it to make one complete revolution. In order to insure this engagement, the toothed wheel *b* is provided at a certain place 55 with an inserted piece *l*, with two large teeth *m*, which extend into the peripheral recess *n* of the main toothed wheel *a*, which is also provided at certain places with notches *o o'*, so that when *o* and *m* coincide the rotation 60 of the wheel *b* is effected systematically. The recess *n* is of such a size that the wheel *b* makes only one revolution and carries with it the crank *e*. The hook *f'* is thereby forced to move in the direction indicated by the 65 arrow in Fig. 1 and to effect an oscillatory movement of the shaft *i* by means of the arm *h*, so that the roller-frame lever *k* is caused to move up and down. When the wheel *b* has completed an entire revolution, its teeth are 70 disengaged from the complete portion of the periphery of the wheel *a*, and the teeth *m* of the inserted piece *l* slide on the bottom of the recess *n* of the wheel *a*, so that the wheel *b* comes to rest. 75

The modification shown in Figs. 3 and 4 differs from that hereinbefore described only in that the crank *e* is not rigidly connected to the toothed wheel *b*, but is adapted to be connected therewith and disengaged therefrom. 80 The connection of the crank *e* with the roller-frame lever *k* by means of the hooked arm *f*, the crank *h* and the shaft *i* remains unaltered. Moreover, in this case no portion of the periphery of the main wheel *a* is removed. Consequently the wheel *b*, which is loosely mounted on its shaft, rotates continuously during the rotation of the wheel *a*. The rotation of the crank *e* is effected as follows: On the shaft *g* of the crank *e*, mounted in the bearing *p*, 85 there is mounted in a usual manner a sliding clutch *r*, which is tapered at the side directed toward the toothed wheel *b*, as will be seen from Fig. 4. Rigidly connected to the shaft *g* is a friction-wheel *s*, which forms, with the inside of the rim of the toothed wheel *b*, a friction-clutch. The friction-wheel *s* is formed by a divided ring, against which there bears in usual manner, at the point *t*, Fig. 3, a 90 95 100

lever u , which is pivoted at v . The lever u has on its free end a pin w , which bears on the conical surface of the clutch r when the latter is moved in the direction indicated by 5 the arrow in Fig. 4, and thus moves the lever u laterally. The wheel s is thus pressed against the inside of the rim of the wheel b , so that the shaft g and the crank e are caused to move therewith. The devices v , u , w , and 10 r are of known kind. Since the crank e has to make a revolution at certain times, the clutch r is only intermittently engaged. For this purpose the forked clutch-lever x is pivoted to the arm y and is provided at its free 15 end with a roller z , which rolls on the inside of the rim of the main wheel a . The wheel a has a projection l , Fig. 3, which when it comes into contact with the roller z moves the lever x , and thereby operates the clutch r . 20 The disengagement of the clutch r is effected by an abutment 2, which acts at the proper moment on the upper portion of the roller z and causes the lever x to move in the opposite direction. When the clutch r is engaged, 25 the crank e makes one revolution and operates the roller-frame lever k in the manner described with reference to the first example until the clutch is disengaged by the abutment 2.

30 Having now particularly described and as-

certained the nature of the said invention and in what manner the same is to be performed, I declare that what I claim is—

1. The combination with a main toothed driving-wheel having a portion of its teeth removed and provided in the blank portion of its periphery with notches, of a second toothed wheel gearing with the main wheel, a toothed piece carried by the said second wheel and the teeth of which piece are adapted to engage in 35 the said notches, an oscillatable inking-roller frame, and connections intermediate said frame and the said second toothed wheel for the purpose specified.

2. The combination with a main toothed driving-wheel, of a second toothed wheel intermittently rotated by the main wheel, a shaft upon which the second wheel is mounted, a crank on said shaft, an arm jointed at one end to the crank and having a hook at the 40 opposite end, an inking-roller frame, an arm carried by said frame and a pin on said arm engaged by the said hook.

In witness whereof I have hereunto set my hand in presence of two witnesses.

WILHELM MAX ROCKSTROH.
